UNITED STATES PATENT OFFICE

2,440,008

SPINACH TUMBLER

George D. Gardner, San Jose, Calif.

Application July 6, 1945, Serial No. 603,534

1 Claim. (Cl. 51—164)

1

This invention relates to an improved means for dry cleaning spinach.

Under present practices spinach is cleaned preparatory to canning, dehydrating or quick freezing the same by passing it through a circular foraminous trommel while at the same time spraying the same with jets of water.

There are certain objections to this type of cleaning. The spinach leaves are fresh and very succulent when brought to the processing factory, and when wetted and tumbled in the trommel the spinach tends to ball-up or twist itself into long strings. Either the balls or strings are hard to handle and it frequently happens that dirt and debris will lodge within the folds of the balled or twisted mass.

It is the primary object of the present invention to provide a means whereby the spinach may be prepared without wetting and so handled that the dirt, small pieces of leaves, twigs and other debris may be readily dislodged and separated from the full sized leaves leaving the latter ready for handling in the processing thereof. This makes for a very much cleaner and better finished product whether the spinach is canned, dehydrated or quick frozen.

A further object of the invention is to produce a simple and inexpensive device and yet one which will be exceedingly effective for the purpose for which it is designed.

These objects are accomplished by means of such structure and relative arrangement of parts as will fully appear by a perusal of the following specification and claim.

In the drawings similar characters of reference indicate similar parts in the several views.

Figure 1 is a side elevation of my improved spinach dry cleaning device.

Figure 2 is an end view of the same.

Figure 3 is a fragmentary section of one of the flat sides of the trommel showing elongated slots formed therein.

Figure 4 is an end view of a modified form of trommel from that shown in Figure 2.

Referring now more particularly to the characters of reference on the drawings my improved device comprises generally a supporting frame F which supports a trough T. The upper portions of the sides of the trough as at 1 stand vertically and the lower portions 2 thereof incline downwardly to terminate in a relatively narrow flush or sluice box 3.

Mounted on rollers 4 within the trough T, is my improved trommel 5 which may be rotated by any suitable drive means as for instance a gear 6

2

driven by suitable motor drive pinion indicated generally at 7.

The trommel 5 is preferably hexagonal in cross section providing six flat walls 8 preferably joined together at their edges by relatively narrow flat webs 9.

These flat sides 8 are each provided with a plurality of elongated slots 10. These slots are of a size sufficient to allow dirt, small pieces of spinach leaves and twigs to pass therethrough, but are of insufficient size to allow the full spinach leaves to pass therethrough or become lodged therein.

In using the device, unwetted spinach is fed into the upper end of the trommel 5 by suitable chute 11. The leaves of the spinach are relatively wide and flat and as fed into the trommel they tend to lay flat on the lower flat sides 8. Then as the trommel turns these flat leaves are gradually up-edged and tumble down into the trough thus discharging dirt, pieces of leaves and twigs from between the leaves and out through the elongated slots 10 into the trough T where they fall down into the sluice box 3. Water may be admitted to the sluice box 3 through an inlet 12 and this water together with the accumulated dirt and debris may be discharged at the opposite end of the sluice box as at 13. The entire sluice box 3 of the trough T lies in a plane which is below the bottom of the trommel 5. The inlet 12 delivers the water into the sluice box 3 at one end and the outlet 13 at the other end is preferably from the bottom of the sluice box and of a diameter relatively much larger than the diameter of the inlet 12. This will allow the water flowing through the sluice box together with the dirt and debris to continuously discharge out of the sluice box so that the water level therein will never rise to a point where it will flow into the trommel.

The relatively flat narrow corner plates 9 prevent the spinach leaves from tending to lodge in these corners.

While I have found that the perfectly flat uninterrupted sides of the hexagonal shaped trommel is probably sufficient to continuously carry the spinach leaves up and turn them over and over, nevertheless, if desired, there may be provided lifting vanes 14 projecting outwardly from the plates 9 as shown in Figure 4 and which will assure the positive carrying up and over of the spinach leaves.

I am aware that trommels, generally for use in separating materials, are old but my inventive concept is that of providing the hexagonal flat

side trommel for the specific purpose of handling the spinach leaves dry and in such a manner as to thoroughly clean them without having to resort to any flush water being applied directly to the spinach leaves within the trommel.

From the foregoing description it will be readily seen that there has been produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claim.

Having thus described my invention what I claim as new and useful and desire to secure by Letters Patent is:

A device for dry cleaning spinach comprising a revolvable foraminous trommel, such trommel being substantially hexagonal in cross section to present relatively wide flat surfaces upon which spinach leaves may lie in their normal unwetted state when moved through the trommel, relatively narrow flat webs connecting adjacent ones of said

flat surfaces, and means associated with the trommel to divert and carry away foreign material which may be discharged through the openings in such foraminous trommel.

GEORGE D. GARDNER.
